ELECTRIC LIGHTING SYSTEM AND MEANS THEREFOR

Filed April 17, 1923 3 Sheets-Sheet 3

UNITED STATES PATENT OFFICE.

WILFRID BROOKE, OF HALE, ENGLAND.

ELECTRIC-LIGHTING SYSTEM AND MEANS THEREFOR.

Application filed April 17, 1923. Serial No. 632,637.

To all whom it may concern:

Be it known that I, WILFRID BROOKE, a subject of the King of Great Britain and Ireland, residing at "Braemar," Laburnum 5 Lane, Hale, in the county of Chester, England, have invented certain new and useful Improvements in or Relating to Electric-Lighting Systems and Means Therefor, of which the following is a specification.

10 My invention relates to improvements in electric lighting systems and the means necessary for carrying the improved system into practical effect.

In particular, the improvements concern 15 enclosed lighting systems suitable to the conditions obtaining in mines, docks, ships, steel-works, warehouses and other places where gas is present or inflammable material is stored or dealt with.

20 I employ an improved method and means which facilitate easy application of the lights, sectionalizing of the lights, or of extending any portion or group of lights or circuits comprised in the system, and I also 25 provide for safe and ready detachment or replacement of any light or switch fitting on a circuit without interrupting the main supply or other lighting on the circuit.

In the system according to my invention, 30 there is or are employed in a circuit one electric cable split connection box or more, preferably arranged to establish contact with a twin core armoured cable at any point or points in its length without the 35 necessity of cutting the cable conductors in the case of through going cables. This is effected by splitting the connection box or boxes or making same in sections or halves adapted to clamp the cable and house the 40 bared portions.

Broadly I employ terminal or connection boxes split in a manner to enable connections to be made with a cable without cutting the cable, the latter only requiring its cores 45 bared in two places and attached to the terminals and enclosed by a clamping or screwing together process of the split box elements.

I also use a lamp-holder section with 50 lamp and plugs which plug into the split terminal or connection box, said lamp-holder section being held to the former by screwed or other locking devices, the jointing or joint making portions of the two being machined and socketing together thus

rendering the connection substantially flame proof.

For the connection of and establishment of an auxiliary circuit with the primary cable I use a plug switch box structure which 60 can be combined with the split terminal or connection box or which may take the place of the detachable lampholder structure removed from a split terminal or connection box. I may employ any suitable switch such 65 as a double pole double fused plug switch and this may be constructed to prevent plugging in or withdrawal when the switch is in the "on" position. The switch may be such as to make the circuit quickly, say by a movement of the operating part through 70 90°.

The attached drawings adequately illustrate my improved system and the means necessary to carry same into practical effect.

In the said drawings:—

Fig. 1 is a front elevation, one half in section, showing the split terminal or connection box, the main cable glands, contact devices, the lamp and the support for the lamp casing, etc.

Fig. 2 shows a plan view of the split connection box, the swing fastening bolts, etc.

Fig. 3 is a detail view of a swing fastening bolt device for securing the detachable lamp holder or other fitting to the lower 85 half of the split connection box.

Fig. 3^a shows a key for turning the nut on the swing bolt.

Fig. 4 is a plan view showing the insulation disc with cable clamps and the sockets 90 for the plugs which are fixed in the detachable lamp supporting casing.

Fig. 5 is a plan view of the lamp supporting detachable casing, the swing fastening bolts. The view shows the lamp plugs, 95 fuse, &c.

Fig. 6 is a detail end view of one of the cable glands which may be examined with Fig. 1.

Fig. 6^a is a detail view.

Fig. 7 shows an elevation of a split connection box for the main cable with a socketing detachable box fixed thereto having a switch and provision for the leading away of an attached or connected cable to establish an auxiliary circuit for lamps, etc.

Fig. 8 is a sectional elevation of Fig. 7, the section being taken at right-angles.

Fig. 9 is a plan view of the insulated disc which is fitted in the detachable box struc- 110

ture which carries the switch, the view showing the plugs, the fuses, the switch spindle and its cross-head, etc.

Fig. 10 is an underneath plan view of Fig. 9 with the insulated disc inverted or turned over to the right, and showing the switch and contacts more clearly than the other views, the switch being shown in the "off" position.

10 Fig. 11 is a plan view showing the switch operating handle and the removable bottom cover for the socketing box of the switch.

Fig. 12 shows in separate detail elevation the main element of the rotatable switch in 15 the "on" position.

Fig. 13 is a diagram illustrating a main cable with split connection boxes, etc., applied according to my invention, as also split connection boxes with switches and auxiliary cables with lamps of various types, &c., applied thereto, the diagram indicating possible schemes.

According to my invention I use a main electric cable such as is marked *a* in Figs. 25 1, 2, 6^a and 13, and this may be of the insulated twin core armoured type, and to this I attach my fittings at any place or places in its length. I am enabled to do this without the necessity of cutting such cable conductor in the case of through going cables. This I accomplish in the case of the attachment of a lamp, by making the connection box in halves or sections as for example an upper half *b* and a lower half *c*, the two 30 halves being secured together by studs *c'* engaging registering lugs or ears on the halves. To the upper half *b* the insulating disc *d* is removably fixed as by the use of screws *d'*. This insulating disc has a distance piece *d''* (which serves to separate the bared cores of the cable) and cable clamps *d''* with detachable caps fixed by screws.

In effecting a connection with the main cable, the same in denuded of its armouring 45 for a few inches and the twin wires of the cables are bared and fixed by the cable clamps *d''*, *d''*. The main cable *a* passes through the split coned extension sleeve *b''*, *c''* in the box halves *b*, *c* and upon said split 50 coned extension sleeves fit the internally coned glands *e*, which are shown as formed in two parts with bored ears *e'*, the bored ears fitting screwed spindles *e''*, *e'''* cast in the box halves *b*, *c* and being held in place by 55 nuts *e''*. Provision is made for "earthing" the case of the cable connection box to the cable armouring in any approved or convenient manner. In the construction illustrated the armouring wire of the cable is 60 intended to be clamped between the outer surface of the coned extension sleeves *b''*, *c''* and the inner coned bore of the cable glands *e* (see Fig. 6^a).

In the insulating disc *d* are fixed metallic 65 contact sockets *d''* see Figs. 1 and 4.

The lower half of the split connecting box *c* has a flange *c''* and is accurately bored and machined, or otherwise contrived, to ensure substantially a gas and water-tight connection with a combined fitting and to 7 obviate any danger from sparking. The connection boxes may in all cases be filled with bituminous or other insulating material on assembly if desired.

To co-operate with the split cable connection box, is provided the lighting or other combined fittings, each consisting of a socketing element such as the combining lamp support *f* which has a turned or machined spigot *f'* and flange *f''* and which sockets to 80 the split box element *c*, as Fig. 1 clearly shows.

The attachment is made by swing bolts, or in other fashion, the drawing showing swing bolts *g* fulcrumed on a pin *g'* held in 85 jaws *g''*, the swing bolts carrying a recessed cylindrical cup *g'''* with tooth *g''*, the nut *g''* being housed in the recess and the tooth *g''* engaging the slot *g''* in the slotted lug *g''* when the nut *g''* is screwed down. With the 90 nut *g''* being recessed in the cylindrical cup *g'''*, a special type of box-key (such as that marked *g''* in Fig. 3^a) is necessary for manipulating the nuts *g''*.

The socketing element *f* which is locked 95 to the split connecting box *c*, as indicated, has a partition *f''* which supports the connecting plugs *f''*, *f''* which are pressed into and engage the sockets *d''*, *d''*, the current passing through plug *f''* through the fuse 10 *f''* and wire *f''* to the lamp holder *f''* supported by the partition *f''* and back through the wire *f''* and the plug *f''*. An incandescent lamp *f''* is shown applied to the lamp holder *f''* and this lamp is enclosed by a glass 10 of any kind, as for example the glass such as *m* shown in Fig. 1. A metal guard is also preferably fitted and this may be a guard *m'* which is cast along with a gallery *m''* for the glass *m* and a flange *m'''* which is 110 fitted to the socketing element *f* by screws *m''* or other simple means.

It will be noted that the machined spigot *f'* is of ample length to slide closely into or 115 to the body portion of the split connection box element *c* and such spigot is preferably of circular shape. One object is to ensure the breaking of current in a confined space should the enclosed lantern be removed whilst the lamp is burning. A further important object is that whilst removing a lantern its case or box (by reason of the machined spigot *f'*) maintains a metallic connection with the earthed split connection 120 box until after current is broken on the plug contacts thereby protecting the attendant from shock if there should happen to be a leak on the fitting which is being withdrawn and this provision for safeguarding is a matter of consequence. 130

- If an auxiliary cable is to be attached in place of a lamp fitting, I use the same split connection box made in parts and which is connected to the main cable by bearing the 5 cable and without cutting the same. This is a split connecting box identical with that already described and made in two halves b c and having the two cores of the cable connected as described.
- 10 The connection for the auxiliary cable is made in a built-up box which is interchangeable for the built-up lantern supporting element f . This built-up box is, as a whole, marked h and fashioned with 15 a long spigot h' accurately machined and which sockets in the box half b . It has a flange h^2 , swing bolts g and locking recessed cups g^3 and projections and nuts g^4 which lock the built-up box h to the 20 half b as is clearly shown in Figs. 7 and 8.
- In this built-up box is fixed an insulating disc i , which may be built-up, the same having two plugs i' , i'' and two fuses i^2 , i^2 . The plugs i' , i'' are pressed into and engage the connecting sockets d^4 , d^4 in the insulating disc d thus connecting the said plugs up to the main cable a .
- The built-up switch box h has an auxiliary cable receiving sleeve h^3 with tapered 30 or conical exterior and a gland box formed in two parts h^4 h^4 having bored ears which fit screwed spindles h^5 cast-in the box, the gland elements being held by nuts h^6 all as already described with respect to the 35 main cable glands.
- The parts marked i^4 , i^4 are distance pieces of insulating material which prevents the fuses i^2 from being located across any wrong pair of terminals.
- 40 The switch shown, is of the rotary double pole type and makes and breaks the circuit by rotation through 90° .
- In the construction shown, the spindle of the switch is marked j and has a shaped 45 cross-head j' which engages an undercut socket j^2 attached to the insulating disc d the purpose of this shaped cross-head being to prevent detachment of the switch unless in the "off" position.
- 50 The cross-head is shown in the "off" position in full lines Fig. 9, and, it will be appreciated that said cross-head and spindle can only be withdrawn when in the "off" position because when in the "on" position the cross-head is locked in the socket j^2 as shown by the dotted lines in Fig. 9.
- The switch spindle carries an insulated drum in the form of a snail j^3 with mid-disc j^4 dividing the snail into two parts with four faces or segments to each of the two parts. There are two brass or conducting segments j^5 j^5 located in the upper part of the snail and metallically connected together to form a through going circuit, the segments being disposed in diametrically opposite positions on two of the four faces of the snail. Similarly two other conducting segments j^6 , j^6 are provided in the lower part of the snail which are metallically connected to form a through going 70 circuit but are located in position 90° from the ones in the other half of the snail, as will be understood from Figs. 10 and 12, and the following description. I also provide two spring contacts k , k , k' , k' for 75 each portion of the drum or snail, as shown most clearly in Fig. 10, these spring contacts being diametrically disposed in pairs, one pair being located 90° in advance of the other pair so as to co-operate with the 80 conducting segments on the snail or drum, whereby the two paths forming the double pole circuit can be completed or broken by a quarter revolution of the spindle j .
- In the drawing, Fig. 10, the switch is 85 shown in the "off" position, but on rotating the snail or drum 90° the current passes through the plug i' and fuse i^2 and down the contact support k^2 through the contact k and the metallic segments j^6 , j^6 of the 90 rotatable snail j^3 , through the contact k to the contact support k^7 to which one of the twin cores of the auxiliary cable is held by the pinching screw k^6 . The other core of the auxiliary twin core cable is pinched 95 by the screw k^5 to the contact supporting post k^4 and the current passes along contact k' to the metallic segments j^5 , j^5 of the rotatable switch through the contact k' the port k^8 the fuse i^2 and the plug i' . 100
- It will be understood that the auxiliary twin core cable enters the switch box through the sleeve h^2 coned on its exterior face and that the armouring is clamped thereon by the cable gland h^4 .
- The switch box bottom is enclosed by a cover k^9 fixed by screws k^{10} and said cover k^9 has a hole or bearing at k^{11} through which the switch spindle j passes. On this cover four positions are marked, two "on", 110 and two "off", see Fig. 11.
- The switch operating handle is marked k^{12} and has a boss k^{13} which is bored right through, as is the end of the spindle, a pin k^{14} securing the said handle to the spindle. The boss of the operating handle has a 115 pointer k^{15} which indicates either the "on" or "off" position, and, it will be understood, that in the "on" position it is impossible to unplug or disconnect the switch box structure because the cross-head j' by engaging the undercut socket j^2 locks the switch box structure to the insulating disc d as already set forth.
- The construction of the switch indicated 125 might be considerably varied and I do not limit myself as to this so long as a detachable switch box structure is used capable of being combined with a split connection box applied to a cable or main in lieu of a lamp 130

structure and interchangeable therefor as herein related.

The Fig. 13 gives a good idea of the uses and possibilities of my invention, as, in this figure I indicate a main cable with split connection box structures applied thereto.

At A is shown a structure with split connection box for attachment to the cable and interchangeable box switch combined therewith and an auxiliary cable a' connected. On this cable a' split boxes and well glass lamps are fitted. Proceeding, I show at B a split cable connecting box capable of receiving either a switch or a lamp. At C I show a further connection to the main cable a with switch box, and an auxiliary cable a^2 with split connection boxes and bulk-head type of lamps with metal guards.

Further along the diagram, is shown another auxiliary cable a^3 with a sub auxiliary cable a^4 connected therefrom, and so on, the additional showings needing no further description, being obvious, save that where a split connection box is shown with-
out socketing box for lamp or a box for switch a detachable cover plate marked a^5 is fitted and screwed in place to seal up the box, and shrouds of insulating material are preferably applied to prevent accidental contact being made with the terminals or sockets.

It will be clearly understood that if it be desired to extend the circuit or system by leading out a branch or extension cable from any point, a length of cable with a further number of cable connection boxes could readily be assembled, say in the workshop, in the manner described and provided at one end with one of the aforementioned switches. To connect up the branch or extension circuit to the main system the switch would be plugged into or applied to the most convenient connection box, either by removing a lantern fitting or a protecting cover in case the particular connection box is sealed up. Where a lantern has been removed to accommodate a switch from a position where a light is particularly required it may be replaced by assembling a connection box on the branch or extension near the switch. Other branch or extension circuits can in like manner be provided to form the complete circuit or network. In order to obviate a long main circuit such as is usual in mines at present, the mains may be sectionalized or made in lengths and provided with a suitable number of connection boxes in each section and each switch assembled at the commencement of the second and each subsequent length of cable or any of them which would be plugged into the last connection box of the preceding section. Thus it becomes an easy matter to locate faults in the system by being able to cut out the various sections.

The location of faults is also facilitated by the provision of separate fuses for each lighting fitting or lantern whereas the usual present practice is to use only one set of main fuses for the whole system. A further feature of my invention is that if a lamp in any particular lantern fails, or the fuse becomes "blown", that particular lantern may be readily withdrawn and replaced by another complete lantern without interrupting the other lighting on the same circuit. The repair of the faulty lantern could thus be carried out at any convenient time or place as it does not involve interfering with the other lighting on the system and when repaired may be used for replacing any other lantern in the interchangeable system.

Another feature of the system is that it lends itself to being extended at will in any direction from any one of a number of points or connection boxes.

I declare that what I claim is:

1. For electric lighting purposes of the kind specified, a split connection box comprising socketing elements adapted to clamp on a cable without cutting same, inlet and outlet apertures, cable glands, an insulating disc, clamps for the cores of the cable housed in said box, sockets for current conducting plugs, means to clamp the socketing elements together and an applied cover plate.

2. For electric lighting purposes, a split connection box, comprising socketing elements adapted to clamp on a cable without cutting same, inlet and outlet apertures for the cable, an insulating disc, clamps for the cores of the cable enclosed in the box, sockets for current conducting plugs, means to clamp the socketing elements together, and an interchangeable combining box with spigot and clamping devices, the interchangeable combining box carrying an electric lamp, and means for protecting the lamp.

3. For lighting schemes of the kind indicated, a split connection box consisting of connected elements adapted to clamp about a cable, entrance and outlet apertures for the cable, an insulated structure secured in the split connection box, cable clamps in said box for the cores of the cable, plug sockets housed in the box, a socket in the lower element of the split connection box, an interchangeable and combining box element, movable fixing means for securing the latter, a spigot on the combining box adapted to fit the socket, and plugs on the combining box capable of engaging the plug sockets.

4. For lighting schemes of the kind indicated, a split connection box having combining parts adapted to clamp to a cable, inlet and outlet apertures for said cable, clamping means for the cable, an insulating de-

vice, cable clamps inside the box for the cores of the cable, sockets in the insulating device, an interchangeable box combining with the split connection box, a machined 5 socket thereon socketing with respect to the split connection box, fastening means for securing the split elements together, an insulating device on the interchangeable box, plugs thereon, a lamp holder, a support for 10 an enclosing glass all whereby interchangeable lighting devices can be applied to a cable without cutting the latter.

5. For lighting schemes of the kind indicated, a split connection box made in parts, 15 and adapted to fit a cable, inlet and outlet for the cable, clamps for the cable, an insulated device in the split connection box, clamps for the cores of the cable therein, 20 sockets, an interchangeable combining box, a spigot and flange thereon, means for fixing

the interchangeable combining box to the split connection box, an insulating device in the former, plugs for connecting the interchangeable combining box with the split connection box, a lamp holder, a gallery and 25 a guard for the lamp and whereby the lamp is protected and fixed to the interchangeable combining box.

6. For the indicated purposes, an electric light connection box, sockets therein, a detachable lantern structure, a socketing spigot on said structure, plugs in said structure, a machined opening in the connection box, the lantern structure combining with the connection box and producing a confined space 30 and whereby "earthing" is ensured until complete withdrawal of the plugs as related.

In testimony whereof I have signed my name to this specification.

WILFRID BROOKE.
